DESIGN FOR AN ARMORED AUTOMOTIVE VEHICLE

Carroll M. Smart, Detroit, Mich.

Application December 31, 1943, Serial No. 112,133

Term of patent 14 years

(Cl. D14—3)

To all whom it may concern:

Be it known that I, Carroll M. Smart, a citizen of the United States and a resident of Detroit, in the county of Wayne and State of Michigan, have invented a new, original, and ornamental Design for an Armored Automotive Vehicle, of which the following is a specification, reference being had to the accompanying drawings, forming a part thereof.

In the drawings:

Fig. 1 is a front perspective view of an armored automotive vehicle showing my new design. Fig.

2 is a rear perspective view showing the same as it appears with the side shield members in lowered position.

The characteristic features of my design reside in the portions shown by means of full lines in the drawings.

I claim:

The ornamental design for an armored automotive vehicle, substantially as shown and described.

CARROLL M. SMART.
